UNITED STATES PATENT OFFICE.

CHARLES S. SAWYER, OF NEW YORK, N. Y.

CARD CLIP OR HOLDER.

1,198,062.

Specification of Letters Patent. Patented Sept. 12, 1916.

Application filed December 1, 1915. Serial No. 64,484.

To all whom it may concern:

Be it known that I, CHARLES S. SAWYER, a citizen of the United States, residing at New York, in the county of New York and State of New York, have invented a certain new and useful Improvement in Card Clips or Holders, of which the following is a specification.

My present invention pertains to an improved card clip or holder, the construction and advantages of which will be hereinafter set forth, reference being had to the annexed drawings, wherein:

Figure 1 is a perspective view of the clip; Fig. 2 a longitudinal vertical sectional view; Fig. 3 a similar view showing the clip in position between two books of a pile; Fig. 4 a like view with a card inserted in the clip or holder; and Fig. 5 a front view, as in Fig. 4.

The object of the invention is to provide a simple and effective card clip or holder, one which while economical and readily manufactured, is also easily positioned and effectively holds the card in proper position.

The holder is formed from a single piece of metal cut and bent to form. The main body of the structure may be said to comprise a base plate 1, preferably rounded at its rear end; a front or face plate 2, extending upwardly from the forward end of the base and inclining slightly to the rear of the vertical and likewise preferably rounded at its top; and a finger 3. Said finger is formed as an extension or continuation of a spring tongue or member 4, which, together with the finger, is cut out of the sheet of metal of which the base and front members are formed. The tongue 4 is slightly longer than the base 1 and as a consequence the finger 3 stands slightly forward of the front or face plate 2, see Fig. 2. The finger is preferably given a slight inward curvature, as at 5, near its upper end, while the extreme upper end is outwardly curved, as at 6.

When the parts are being brought to form, tongue 4 will preferably be thrown downwardly to a slight extent, below the body 1, the parts normally standing in the relative positions shown in Fig. 2.

A pair of stop lugs or ears 7 are also struck out of the front plate 2, said ears projecting outwardly therefrom and preferably lying in the same plane as base 1.

In use, when the base or body member 1 is inserted between two books, or the like,

the parts assume the positions shown in Fig. 3, tongue 4 being forced upwardly by the pressure exerted by the books and, as a consequence, the upper end of finger 3 will be caused to approach the face plate, if in fact not to enter the opening 8 in said plate produced in the process of forming the finger. A card (denoted by 9) inserted behind the finger will force the same forward to a slight extent, thereby causing sufficient friction to hold the card in position. The card will be pushed down behind the finger until it comes to rest against lugs 7 which serve to maintain it in its proper or squared position.

The tension of the spring finger 3 may be varied by bending the tongue or the finger, or both, as will be readily understood.

It will be at once seen that there are no loose parts in the present structure to become lost; that there are no jointed parts; and in fact, that the device is simple and strong and easy of placement.

Having thus described my invention, what I claim is:

1. A card-holder formed from a single piece of metal and comprising a base plate and a face plate standing at approximately right angles to each other, a tongue extending forward from the rear portion of the base plate, and a clamping finger extending upwardly from the tongue and standing slightly forward of the face plate.

2. A card-holder formed from a single piece of metal and comprising a base plate and a face plate standing at approximately right angles to each other, a tongue extending forwardly from the rear portion of the base plate to a point slightly in front of the face plate, and a finger extending upwardly from the tongue in front of the face plate, said finger, adjacent the upper portion, curving inwardly toward the face plate while the extreme upper end is inclined outwardly therefrom.

3. A card-holder formed from a single piece of metal and comprising a base plate and a face plate standing at approximately right angles to each other, a tongue extending forwardly from the base plate, a clamping finger extending upwardly from the tongue in front of the face plate, and a pair of lugs extending outwardly beyond the face plate adjacent the lower end thereof and forming stops or rests for the inserted card.

4. In a card-holder, the combination of a

base plate, a face plate projecting upwardly therefrom, a tongue extending forwardly from the rear portion of the base plate, said tongue lying, in part, below the lower face 5 of the base plate, and a finger extending upwardly from the forward end of said tongue in front of the face plate, all of said parts being formed from a single piece of metal bent to form.

10 5. A card-holder formed from a single piece of spring metal and comprising a base plate, a face plate standing at an angle thereto, a tongue extending forwardly from the rear portion of the base plate and being

thrown downwardly to a slight extent below the lower face of the base plate, and a finger extending upwardly from the forward end of the tongue, in front of the face plate, whereby when the base plate and tongue are forced inwardly between two 20 books or the like the tongue will be forced upwardly and the upper end of the finger will be thrown inwardly toward the face plate.

In testimony whereof I have signed my 25 name to this specification.

CHARLES S. SAWYER.
